MULTIPLE UNIT RESISTOR ASSEMBLY

Charles H. Stevens, Jr., Cornwall Bridge, Conn.

Application July 8, 1953, Serial No. 366,731

6 Claims. (Cl. 323—74)

1

The present invention relates to apparatus for the control of the supplying of current to welding units and more particularly to improved apparatus for individual control by the individual welder whereby the current requirements of his job may be fulfilled without affecting the current requirements for other welders plugged into the same apparatus. The present invention may be employed in combination with apparatus such as is shown and described in my copending application filed of even date or with other apparatus providing constant voltage in the manner of my referred to apparatus.

An object of my present invention is to provide an improved resistor assembly for welding units wherein the desired amperage can be supplied for use in a particular welding unit by simple manual actuation of switches, various combinations of actuated switches placing preselected of a group of resistances in parallel with respect to each other and in series in the circuit to the electrode holder of a welding unit so as to give a wide range current for that unit as required.

Another object of the present invention is to provide an improved resistor assembly for multiple welding units which is of rigid and well protected construction so as to withstand the hard usage to which such devices are normally subjected.

A further object of the present invention is to provide a substantially completely enclosed resistor assembly for supplying current to multiple welding units wherein the overall size and weight are at a minimum as opposed to other arrangements each of which normally accommodates but a single welding unit.

Still another object of the present invention is to provide an improved resistor assembly embodying removable drawers housing resistances and providing mountings for switches controlling inclusion of such resistances in the electrical circuit so that controls for a single welding unit are essentially separate and entirely removable for repair and replacement without requiring major disassembly operations or the like.

A still further object of the present invention is to provide an improved resistor assembly for multiple welding units wherein a single supply cable feeds all of said units by the use of bus bars, the drawer assemblies being so cooperatively related to such bus bars that electrical disconnection is effected prior to removal of the individual drawers for safety in making repairs on a single drawer assembly without requiring disconnection of the main power source.

2

Another object of the present invention is to provide an improved resistor assembly wherein there is flexibility of control by the individual welders without regard to requirements by other welders.

Still another object of the present invention is to provide improved resistances which embody ample support with maximum cooling of the resistance wires along with unrestricted longitudinal expansion and contraction of the resistance wires.

Various other objects and advantages will become apparent from the detailed description to follow.

15 In the drawings:

Fig. 1 is a perspective view of my entire improved resistor assembly showing a cable plugged into one of the resistor drawers, the cable being adapted to be connected to the electrode of a welding unit, and also showing one of the drawers partially withdrawn to expose the resistance coils housed therein;

Fig. 2 is a view of part of the bus bar assembly showing the connection for the inlet cable and also the knife switch arrangement whereby each of the drawers is detachably electrically connected with the bus bar assembly;

Fig. 3 is a top plan view of the arrangement of Fig. 2 with parts being broken away;

Fig. 4 is a longitudinal sectional view through one of the switch plungers of which several are employed with each drawer of resistors;

Fig. 5 is a rear perspective view of the assembly of Fig. 1 with part of the screening removed so as to expose the bus bar assembly at the rear of the plurality of drawers and also showing details of the framework;

Fig. 6 is a perspective view of one of the drawer resistor assemblies entirely removed and showing the switch arrangement on the inside of the front plate of the drawer;

Fig. 7 is a top plan view of the drawer assembly of Fig. 6;

Fig. 8 is a longitudinal vertical sectional view taken substantially on the plane of line 8—8 of Fig. 7;

Fig. 9 is a front elevational view showing at least one drawer assembly when mounted in place in the supporting framework;

Fig. 10 is an enlarged detail view of one of the resistance coils, partly in section and showing the manner in which the plurality of relatively movable porcelain blocks support the coils of wire for cooling and for freedom of expansion and contraction;

Fig. 11 is a vertical transverse sectional view taken substantially along the plane of line 11-11 of Fig. 10;

Fig. 12 is a vertical sectional view through a portion of the front plate of one of the drawer assemblies and showing the details of the spring switch contacts and the cooperation of the switch plunger therewith;

Fig. 13 is a detail view showing the pair of spring switch contacts as mounted on the insulating block therefor;

Fig. 14 is an end elevational view of the arrangement of Fig. 13;

Fig. 15 is a detail sectional view showing the cam-surfaced stud and bracket assembly which is carried by the front plate of each drawer.

Fig. 16 is a fragmentary schematic circuit and structure view of the upper and lower resistance coil arrangement of Fig. 8 with supply and work leads added and also schematically shown.

Referring more particularly to the drawings it will be seen that my improved resistor assembly 10 is comprised of a supporting framework designated generally by the numeral 12 and providing multiple drawer-receiving spaces 14, bus bar means 16 and a plurality of drawer assemblies 18.

The supporting framework 12 is best shown in Figs. 1, 5 and 9 as comprising four upstanding front corner posts 20 and 22 and rear posts 24 and 26, the front posts being joined adjacent their tops, midsections and bottoms by cross bars 28, 30 and 32, while the rear posts are similarly joined at 34, 36 and 38, angle iron being used because of its high strength and facile assembly into the construction shown. Additionally, vertical divider and rigidifying bars are provided at the rear of the framework at 40, 42 so that as viewed from the rear the framework is divided into six subdivisions although it will be understood that it is within my contemplation to construct my assembly for use by any practicable number of welding units.

As viewed from each of the sides there are provided horizontal upper, intermediate and lower joinder bars 44, 46 and 48 joining the front and rear corner posts at each side. Intermediate the ends of the framework, the cross bars are joined by drawer supporting irons 50, 52, 54 and 56 and also the upper drawer guides 58 and 60 at the upper ends of the rigidifying bars extending forwardly to the cross-bar 28.

In addition to the foregoing the framework includes bus bar supporting means in the form of three upstanding angle irons 62, 64 and 66 located substantially centrally between the upstanding bars 24, 40; 40, 42; and 42, 26.

The entire framework described is preferably thru-welded at all joints although it will be understood that other modes and means of forming the joints may be employed as desired.

For protective reasons I provide the angulated roof member 68 over the top of the framework to protect the interior from precipitation and falling objects, etc., bolts or other attachment elements as at 70 securing the roof member 68 to the top of the framework. At the top front of the framework and as shown in Fig. 1, there is provided an overhang element 72 in the form of an elongated double thickness strip of metal which is secured by the attachment means in the form of bolts at 74, the overhang being provided to protect the switch plungers of the drawer assemblies, to be described in detail here-

inafter, from falling objects such as might be encountered on the job.

The framework is also provided with wire screening covering the sides and rear of the framework at 76, 78 and 80, screws preferably being employed to secure the angle irons as at 32 and 34 over the corners of the wire screen to hold the same to the framework. The screening over the lower central drawer space at the rear is preferably removable so as to provide access to the cable connection for the inlet power, as will presently be described.

As seen best in Figs. 2, 3 and 5, the bus bar means 16 includes horizontal bus bars 86 and 88 joined by the single vertical bus bar 90 at their centers. The horizontal bus bars 86 and 88 are secured to insulating pads, as of Bakelite, 92, 94 and 96 and 98, 100 and 102 by bolts 104, the insulating pads in turn being secured to the bus bar supporting angle irons 62, 64 and 66 by bolts 106. For supplying electrical power to the assembly and particularly to the bus bar arrangement, an inlet cable 102 has its attachment end 110 secured to the vertical bus bar 90 by the bolt 112, as shown in Fig. 2, it being understood that the cable is desirably the output of such an arrangement as is shown and claimed in my referred to copending application. For electrically connecting each of the drawer assemblies to be described hereinafter, I provide switch means in the form of spring clips 114 and 116 as seen best in Figs. 2, 3 and 5. Each clip includes a bus bar embracing portion 118 and resilient fingers 120 and 122. One of the spring clips 114 is secured by a bolt at 124 to the respective bus bar and the other spring clip of the pair is secured by a bolt extending through the insulating pad such as at 94.

As seen in Fig. 1, there are provided six drawer assemblies 18, one for each welding unit, and a power take-off cable such as at 126 is provided for each welder for coupling in the socket 128 at the front plate 130 of each drawer assembly.

Figs. 1, 6, 7, 8 and 9 show one of the drawer assemblies 18 as comprised of front plate 130, rear plate 132, longitudinally extending bars 134 and 136 at the sides of the bottom and inclined rigidifying straps at 138 and 140 at each side joining the rear and front plates to the longitudinally extending angle iron bars 134 and 136. The rear plate 132 has a centrally located opening through which a threaded stud 142 extends. Nuts 144 and 146 and Bakelite washers 148 and 150 on opposing sides of the rear plate are employed to secure the stud 142 in insulated relationship with the rear plate 132. The stud 142 has its outer end bifurcated and a knife switch element 152 is received therein and secured thereto by screws 154.

A plurality of resistances as at 156, six as shown, are mounted in each drawer assembly. As seen best in Figs. 10 and 11, each resistance 156 is in the form of a wire coil and is comprised of a mounting rod 158 of square or other non-circular cross-section having threaded ends at 160 and 162 for mounting in the front and rear plates 130 and 132, as by nuts 164. Each resistance further includes a plurality of porcelain blocks 166 having a relatively flattened cross section but with substantially cylindrical peripheral surface portions at 168 and 170, which cylindrical surface portions are only a small portion of the surface of a complete cylinder. The surface portions 168 and 170 have grooves 172 formed therein which are substantially in the locus of

a helix, the widths and depths of the grooves being such as to support the coiled wire 174 with a minimum of contact and with freedom of air circulation beneath the wire and within each groove as at 176.

The plurality of blocks 166 are alternately relatively rotated through 90° relative to each other and since they have openings therethrough corresponding to the cross section of the rod 158 the blocks will be held in their desired relationship. Pins 173 and 180 are engaged through the rod 158 spaced from the end blocks so as to afford relative longitudinal movement between the blocks upon expansion or contraction of the wire of the coil 174. Prior to assembling the resistance unit the wire is preformed into a coil and the blocks are engaged on the rod as described and shown. Next the wire coil is threaded into the grooves so as to resiliently hold the blocks in a longitudinal relationship which is free to vary as the temperature varies.

Adjacent the rear plate 132 each coil has its wire terminal extended for connection to the transverse bus bar 182 as at 184, 186, 188, 190, 192 and 194, the bus bar 182 in turn being connected to the inner end of the stud 142 so that all of the resistances are in parallel relative to each other and in series with the inlet cable 108. The opposing end of each coil has its wire terminal as 195 extended for connection to one of the individual posts as at 196, in Fig. 12, a pair of nuts 198 securing the same to the post. It is to be noted that each coil is connected to but one of the posts as 196 and each post in turn is electrically connected with but one plunger clip as 200.

The plunger clips are best shown in Figs. 12-14 as being substantially U-shaped in form with the leg portions 202 and 204 somewhat bowed and resilient so as to resiliently electrically contact the plunger 206 engageable therebetween. A pair of such clips 200 and 201 are secured in longitudinally aligned spaced and insulated relationship by the posts 196 and 197 engaged through the mounting Bakelite insulator block 208. For enhancing the resiliency of the clips, I provide steel springs 210 which in side elevation as in Fig. 13 are S-shaped and in end elevation as in Fig. 14 are substantially U-shaped with the legs 212 and 214 bowed to conform with the leg portions 202 and 204 of the clips. The bight portion 216 is positioned so as to be beneath the plunger presently to be described.

Whereas the posts 196 and clips 200 are individually electrically isolated by the insulation 199, the clips 201 and the posts 197 are all electrically interconnected with each other by the bus bar 218 which in turn is connected with the fuse 220 by the bolt 222. The other end of the fuse has connected thereto at the bolt 224 a conductor 226 which extends to the bracket 228, 229 mounted on the inside of the front plate at its center for electrical connection with the split and cam surfaced stud 230, the latter constituting the outlet to which a welder connects his cable as the cable 126 in Fig. 1.

In order to include a resistance in the circuit, I provide a plurality of plungers 206, one for each coil. As shown in Fig. 4 a plunger 206 is disclosed as including a Bakelite body 232 molded so as to include a finger-engaged enlarged head 234, and an elongated reduced diameter portion 236 on which the Bakelite washer 238 is engaged and held in spaced relation to the head 234 whereby withdrawal of the plunger relative to

the front plate 130 is limited, the shoulder at 240 acting to limit inward engaging movement of the plunger. The body 232 has a further reduced diameter portion at 242 and an axial tapped

bore 244. A tubular sleeve 246 preferably of brass is engaged on the reduced diameter portion 242 and has its end turned in at 248 to provide a seat. A steel conical element 250 is engaged on the seat and a flat head screw also of

steel is inserted through the conical element and threaded into the bore 244 with the head 252 tightly abutting the conical element 250 so as to hold the brass sleeve firmly in place on the Bakelite body 232.

15 Referring once again to the resistance coils as shown in Figs. 6-8, I employ six coils the bottom three of which as at 254 are all 80 ampere coils made from No. 4 Nichrome wire, fifty turns. The upper three coils 256, 258 and 260 are made from No. 13, No. 10 and No. 7 Nichrome wire with 75, 52 and 48 turns, respectively, to provide 20 10, 20 and 40 ampere coils, respectively. With such coils the welder, by proper selection and actuation of the plungers 206, can provide in his 25 cable 126 amperage ranging from 10 amperes to 310 amperes in 10 ampere increments. In order not to overload, the fuse link 220 has a maximum capacity of 400 amperes. Of course, the numbers of turns employed, wire size, etc., are by way 30 of example and may be varied to fulfill special requirements.

There is shown in Fig. 16 a schematic view of an electric circuit which may be used wherein S. P. denotes source of power and W denotes work 35 with all other parts of the circuit and structure designated as in the other figures of drawings.

Thus, if a welder requires 80 amperes for a particular job, he merely presses one of the plungers 206 which is identified as controlling the 40 circuit to one of the 80 ampere coils, the plunger by means of the sleeve 246 completing the circuit between the switch or contact clips 200 and 201, as shown in full lines in Fig. 12. Current will 45 then pass from the source through the cable 128, bus bar 90, clip 114, knife switch element 152, stud 142, coil 254, contact clip 200, sleeve 246, clip 201, bus bar 218, fuse clip 220, strap 226, stud 230 and cable 126 to the welding electrode, not shown. Of course, if 70 amperes are required, the plungers inserting the 40, 20 and 10 ampere coils are pressed instead, current flowing in series through the parallel group of resistance coils.

When repairs or replacements are required or if for any reason it is desired to obtain access to the coils or other associate elements within the framework, it is merely necessary to grip the handle 262, as in Fig. 1, and slide the drawer outwardly. For safety the knife switch element 152 breaks contact with the clip contacts 114 and 116 upon initial withdrawing movement of the drawer so as not to have "live" coils exposed.

As this invention may be embodied in several forms without departing from the spirit or essential characteristics thereof, the present embodiment is therefore illustrative and not restrictive, since the scope of the invention is defined by the appended claims rather than by the description preceding them, and all changes that fall within the metes and bounds of the claims or that form their functional as well as conjointly cooperative equivalents, are therefore intended to be embraced by those claims.

I claim:

1. A resistor assembly for multiple welding units comprising a support, plural drawer assemblies

removably mounted in said support, a source of electrical power, each of said drawer assemblies including multiple resistances, switch means releasably electrically interconnecting said source of electrical power with common ends of said resistances in each drawer assembly when the respective drawer assembly is in its non-removed relationship, additional switch means associated with the other end of each of said resistances and associated with an outlet adapted to supply current to a welding unit, said additional switch means being selectively operable to include preselected of said resistances in the electrical circuit so as to control the amperage fed to the electrical outlet.

2. A resistor assembly for welding units comprising a framework providing multiple drawer spaces, a drawer assembly removably mounted in each drawer space, each drawer assembly comprising multiple resistances, a source of electrical power connected with one end of each of said resistances, switch means associated with the other end of each of said resistances and associated with an outlet adapted to supply current to a welding unit, said switch means being selectively operable to include preselected of said resistances in the electrical circuit so as to control the amperage fed to the electrical outlet.

3. A resistor assembly for welding units comprising a framework providing multiple drawer spaces, a drawer assembly removably mounted in each drawer space, said framework having bus bar means behind each drawer space adapted to be connected with a source of electrical power, switch means releasably electrically interconnecting each drawer assembly with said bus bar means, each drawer assembly comprising multiple resistances each having one end thereof connected with a portion of said switch means, additional switch means associated with the other end of each of said resistances and associated with an outlet adapted to supply current to a welding unit, the latter switch means being selectively operable to include preselected of said resistances in the electrical circuit so as to control the amperage fed to the electrical outlet.

4. A resistor assembly for welding units comprising a framework providing multiple drawer spaces, a drawer assembly removably mounted in each drawer space, said framework having bus bar means behind each drawer space adapted to be connected with a source of electrical power, switch means releasably electrically interconnecting each drawer assembly with said bus bar means, each drawer assembly comprising multiple resistances each having one end thereof connected with a portion of said switch means, addi-

tional switch means associated with the other end of each of said resistances and associated with an outlet adapted to supply current to a welding unit, the latter switch means being selectively operable to include preselected of said resistances in the electrical circuit so as to control the amperage fed to the electrical outlet, said first recited switch means including spring clips on the bus bar means and a knife switch element carried by each drawer assembly for engagement with the respective spring clips.

5. A resistor assembly for welding units comprising a framework providing multiple drawer spaces, a drawer assembly removably mounted in each drawer space, each drawer assembly comprising multiple resistances, a source of electrical power connected with one end of each of said resistances, switch means associated with the other end of each of said resistances and associated with an outlet adapted to supply current to a welding unit, said switch means being selectively operable to include preselected of said resistances in the electrical circuit so as to control the amperage fed to the electrical outlet, and a fuse in the electrical circuit between the switch means and said electrical outlet.

6. A resistor assembly for welding units comprising multiple resistances, a source of electrical power connected with one end of each of said resistances, switch means associated with the other end of each of said resistances and associated with an outlet adapted to supply current to a welding unit, said switch means being selectively operable to include preselected of said resistances in the electrical circuit so as to control the amperage fed to the electrical outlet, said switch means including push plungers, and a pair of longitudinally spaced contacts for each push plunger, one of each of said pairs of contacts being electrically connected with the respective push plunger and with a respective resistance while the other is selectively electrically engaged by said plunger and is at all times connected with the electrical outlet.
